DESIGN FOR A JAR OPENER

Russell F. Glasstetter, Bantam, Conn.

Application June 6, 1946, Serial No. 130,458

Term of patent 3½ years

(Cl. D44—29)

To all whom it may concern:

Be it known that I, Russell F. Glasstetter, a citizen of the United States of America, residing in Bantam, county of Litchfield, and State of Connecticut, have invented a new, original, and ornamental Design for Jar Openers, of which the following is a specification, reference being had to the accompanying drawing, forming part thereof.

Fig. 1 is a side perspective view of the jar opener, showing my new design.

Fig. 2 is a top plan view of the same.

I claim:

The ornamental design for a jar opener, as shown.

RUSSELL F. GLASSTETTER.
